ATTORNEY.

UNITED STATES PATENT OFFICE

HARRY G. SMITH, OF DEARBORN, MICHIGAN

AIRPLANE

Application filed May 15, 1930. Serial No. 452,556.

My invention relates to airplanes and more particularly to the vehicle structure, with special reference to the under-carriage or landing gear.

5 A great deal of attention is now being given to stream-lining airplanes in order to reduce wind resistance as much as possible, and in order to obtain more speed and to reduce the fuel consumption. The parasite resistance 10 of the usual landing gear has been very difficult to overcome and this has been partially reduced by providing a stream-line shell to the rear of the wheels, but which is only extended rearwardly from the upper half of 15 the wheel. Retractable landing gears have been proposed, but this method is rather expensive to manufacture and has only proved to be satisfactory on light planes requiring only a lightly constructed landing gear. The 20 larger type of commercial planes require a larger and heavier landing gear and these cannot be readily retracted into the wings or into the fuselage. This problem of reducing parasite resistance is growing greater 25 each year.

It is an object of my invention to reduce the parasite resistance to a minimum by providing a streamlining structure adapted to be supported to the rear of the landing wheel 30 that will more perfectly eliminate this parasite resistance.

Another object of my invention is to construct a streamlined shell that is supported to the rear of the entire wheel for reducing 35 the parasite resistance to a minimum, but which may be readily retracted when making a landing.

A further object of my invention is to facilitate the landing of airplanes provided 40 with streamlined shells to the rear of the entire wheel, and which project below the lowermost point of the wheel by providing means for automatically retracting the said shell upon landing.

45 For a more detailed understanding of my invention, reference may be had to the accompanying drawing, illustrating a preferred form of my invention and in which:

Fig. 1 is a side elevational view of an airplane landing gear structure provided with a

retractable streamlined shell extending to the rear of the wheels and constructed in accordance with my invention;

Fig. 2 is a plan view thereof;

Fig. 3 is a sectional view taken on the line 55 3—3 of Fig. 1;

Fig. 4 is a detailed sectional view taken on the line 4—4 of Fig. 3;

Fig. 5 is a side elevational view of a modified form of construction, and 60

Fig. 6 is an enlarged sectional view illustrating the structure shown in Fig. 5.

The landing gear of an airplane is suspended beneath the plane structure and generally supported by struts attached to the 65 fuselage of the plane. In my drawing (Fig. 1) I have illustrated a fragmentary portion 10 of a fuselage the struts 11 of a landing gear structure which comprises an axle 12 and wheels 13. The wheels are rotatably supported on the axle and are preferably supplied with tires of a sufficient size to carry the load of the plane. These wheels and tires which are usually of considerable size 70 project into the air stream and considerable 75 power is wasted in overcoming this parasite resistance.

I have provided a streamlined shell structure "A" adapted to be secured in place directly to the rear of the wheel. This shell 80 is constructed, as is clearly illustrated, in the drawing, of a shape which may be propelled through the air with a minimum loss of power. Obviously a shell structure which encloses the entire rear portion of the wheel 85 that extends to the rear of the vertical plane containing the wheel axis, and which is curved to follow the air stream as it flows by the wheel, will present a minimum of resistance and will have the least frictional 90 resistance. Such a shell structure is illustrated in Figs. 1 and 5, but it will be noted that this shell when projected rearwardly in a horizontal plane as shown in Fig. 5 and by the dotted lines in Fig. 1, projects below the lowermost point of the wheel. The shell is supported in this substantial horizontal position when the plane is in flight by means of a pin 15 or other suitable lug carried by the shell which engages the shoulder 16 of a stop 95 100

plate 17, carried by the fixed axle or any other fixed part of the landing gear structure. The shoulder 18 limits the upward travel of the shell.

To the rear of the wheel axle, a skid 19 is preferably secured to the shell, this skid being secured at any suitable location and constructed of a predetermined length and positioned at an angle to the horizontal plane. The skid is rigidly carried by the shell and will be the first part of the landing gear to engage the ground on landing. As the plane comes down the skid will lift the tail of the streamlined shell and rotate the same about the axle until it reaches the position as shown in full lines in Fig. 1. The shell is thus rotated to clear the ground and to allow the wheels to roll along the ground. It is noted that the lower position of the wheel is thus uncovered. When the plane rises off the ground the shell will drop again by gravity to the horizontal position that it assumes when the plane is flying.

It will thus be noted that I have provided a structure which is automatically retracted out of the way on landing plane. The pilot need not think about the operation of this mechanism for it is always positively automatically operated as soon as the skid strikes the ground. Furthermore the shell may be constructed as to very lightly contact with the tire so that the rotation of the wheel when rolling along the ground tends to lift the shell or maintain the same in a retracted position.

If found desirable, a cable 25, or other suitable retracting means may be incorporated in the structure so that the pilot may lift the shell if he so desires. Such a cable may be advantageously used in larger planes.

Figs. 5 and 6 illustrate a further modification. In addition to the skid, a brake device or drag may be carried by the shell. This device comprises a shoe 30 which is yieldingly pressed against the tire by the spring 31. Thus as the wheel rotates the shell is positively lifted from the horizontal position to an elevated position and held there because of the friction between the brake shoe and tire. If desirable this shoe may be engaged with a brake drum instead of the rubber tire. This brake device is more useful when used in conjunction with large size landing gear structures. When a streamline shell of usual design is employed which does not cover the entire rear half of the wheel, the skid need not be used. But because of the relative great movement of the wheel when employing shock absorbing devices having an excessive amount of play, a structure as illustrated in Figs. 5 and 6 will be quite useful in elevating the shell out of the way of the ground.

Although I have illustrated but a few forms of my invention and have described in detail but a few applications thereof, it will be understood that various modifications and

changes may be made therein without departing from the spirit of my invention or from the scope of the appended claims.

I claim:

1. A streamline shell for the landing gear of an airplane or the like, comprising a movable shell structure, and means engaging with the ground for automatically elevating said shell structure as the airplane approaches the ground. 70

2. A streamline shell for the landing gear of an airplane or the like, comprising a movable shell structure normally projected below the lowermost point of said landing gear, and means adapted for engagement with the ground for automatically elevating the said shell structure above the lowermost point on said landing gear. 75

3. A streamline shell for the landing wheel of an airplane or the like, comprising a movable shell structure extending to the rear of said landing wheel and enclosing at least that portion of the wheel to the rear of a vertical plane containing the wheel axis, and means for automatically elevating said shell structure as the plane approaches the ground to permit said wheels to engage the ground. 85 90

4. A streamline shell for the landing wheel of an airplane or the like, comprising a movable shell structure extending to the rear of said landing wheel and enclosing at least that portion of the wheel to the rear of a vertical plane containing the wheel axis, and means attached to and depending from said shell structure and adapted for engagement with the ground for elevating said shell structure as the plane approaches the ground. 95

5. A streamline shell for the landing wheel of an airplane or the like, comprising a movable shell structure extending to the rear of the landing wheel and enclosing more than one-half of the wheel and including at least that portion thereof to the rear of a vertical plane containing the wheel axis, and means for automatically moving said shell structure to uncover the lower portion of said wheel. 105 110

6. A streamline shell for the landing wheel of an airplane or the like, comprising a shell structure pivotally supported to swing about the wheel axis, said structure normally extended to the rear of the wheel and enclosing at least that portion of the wheel to the rear of a vertical plane containing the wheel axis, and means automatically operated as the plane approaches the ground to rotate said shell structure for uncovering the lower portion of the wheel to permit the same to engage the ground. 115 120

7. A streamline shell for the landing wheel of an airplane or the like, comprising a shell structure pivotally supported to swing about the wheel axis, said structure normally extended to the rear of the wheel and enclosing at least that portion of the wheel to the rear of a vertical plane containing the wheel axis, 125 130

and a skid depending from said shell structure and adapted for engagement with the ground to rotate said shell structure as the plane approaches the ground for uncovering the lower portion of the wheel to permit the same to engage the ground.

8. A streamline shell for the landing gear of an airplane or the like, comprising a movable shell structure, means for automatically elevating said shell structure as the airplane approaches the ground, and means for limiting the movement of said shell structure.

9. A streamline shell for the landing wheel of an airplane or the like, comprising a shell structure pivotally supported to swing about the wheel axis, said structure normally extended to the rear of the wheel and enclosing at least that portion of the wheel to the rear of a vertical plane containing the wheel axis, means for supporting said shell structure to maintain the same in substantially a horizontal position, and means for automatically rotating said shell structure to uncover the lower portion of the wheel, thereby permitting the wheel to engage the ground.

10. A streamline shell for the landing wheel of an airplane or the like, comprising a shell structure pivotally supported to swing about the wheel axis, said structure normally extending to the rear of the wheel and enclosing at least that portion of the wheel to the rear of a vertical plane containing the wheel axis, means for supporting said shell structure to maintain the same in substantially a horizontal position, means for automatically rotating said shell structure to uncover the lower portion of the wheel, thereby permitting the wheel to engage the ground, and means for limiting the rotating movement of said shell structure.

11. A streamline shell for the landing wheel of an airplane or the like, comprising a shell structure pivotally supported to swing about the wheel axis, said structure normally extending to the rear of the wheel and enclosing at least that portion of the wheel to the rear of a vertical plane containing the wheel axis, means for supporting said shell structure to maintain the same in substantially a horizontal position, means for automatically rotating said shell structure to uncover the lower portion of the wheel, thereby permitting the wheel to engage the ground, means for limiting the rotating movement of said shell structure, and a fixed stop for engaging said shell structure for limiting the rotational movement of said shell structure.

12. A streamline shell for the landing wheel of an airplane or the like, comprising a shell structure pivotally supported to swing about the wheel axis, said structure normally extended to the rear of the wheel and enclosing at least that portion of the wheel to the rear of a vertical plane containing the wheel axis, means carried by said shell structure

and yieldingly engaging the wheel for transmitting the rotating force of the wheel to the shell structure to rotate the said shell structure for uncovering the lower portion of the wheel, and a stop for engaging said shell structure to limit such rotational movement of said shell structure.

13. A streamline shell for the landing wheel of an airplane or the like, comprising a shell structure pivotally supported to rotate about the wheel axis, means carried by said shell structure and yieldingly engaging the wheel for transmitting the rotating force of the wheel to the shell structure for rotating the same, and means for limiting the rotational movement of said shell structure.

14. A streamline shell for the landing wheel of an airplane or the like, comprising a shell structure pivotally supported to rotate about the wheel axis, a brake shoe means yieldingly carried by said shell structure and engaging the wheel to transmit the rotating force of the wheel to the shell structure for rotating the same, and means for limiting the rotational movement of said shell structure.

15. A streamline shell for the landing wheel of an airplane or the like, comprising a movable unitary shell structure normally extending above and below the upper and lower extremities of the landing wheel, and means for moving said shell structure from said normal position to uncover the extreme lower portion of said wheel to facilitate landing.

16. A streamline shell for the landing wheel of an airplane or the like, comprising a shell structure movably supported relative to said landing wheel, and means associated with said shell structure and cooperating with said landing wheel, whereby on rotation of said wheel said shell structure is caused to be moved to facilitate landing of the airplane.

17. A streamline shell for the landing wheel of an airplane or the like, comprising a shell structure supported for relative rotation about the wheel axis, and means cooperating with said wheel for actuating said shell structure to rotate same to elevate same for facilitating the landing of the airplane.

18. A streamline shell for the landing wheel of an airplane or the like, comprising a shell structure pivotally supported to rotate about the wheel axis, a brake shoe carried by said structure and adapted for yielding engagement with the wheel whereby on rotation of said wheel said shell structure is rotated to elevate same for facilitating the landing of the airplane.

In testimony whereof I have affixed my signature.

HARRY G. SMITH.
